C. H. FAY.

INSERT FOR CEMENT OR SIMILAR FLOORS.

APPLICATION FILED SEPT. 25, 1919.

1,419,548.

Patented June 13, 1922.

UNITED STATES PATENT OFFICE.

CHARLES H. FAY, OF NEWARK, NEW JERSEY.

INSERT FOR CEMENT OR SIMILAR FLOORS.

1,419,548.

Specification of Letters Patent. Patented June 13, 1922.

Application filed September 25, 1919. Serial No. 326,339.

To all whom it may concern:

Be it known that I, CHARLES H. FAY, a citizen of the United States, and a resident of Newark, county of Essex, and State of 5 New Jersey, have invented certain new and useful Improvements in Inserts for Cement or Similar Floors, of which the following is a specification.

This invention relates to an improved insert for cement or other mastic floors and is adapted to be used for the passage of pipes or similar elements through a floor. There has been considerable difficulty in a number of trades to provide for the 15 passage of pipes through such floors, in that if not carefully done, the opening is clogged and requires the removal of concrete and cement before the pipe can be passed through, or if due care is taken to 20 see that the openings are properly and adequately aligned, it takes considerable of the floor layer's time, and the present invention is designed to provide a device that can be easily installed, has no intricate 25 parts thereon to be adjusted, and when in place is substantial enough to permit the laying of the concrete floor as ordinarily done, and when completed there is a 30 properly aligned and properly sized opening for a pipe.

The invention is further designed to provide a device of this kind which can be quickly proportioned according to the thickness of the floor into which it is to be 35 placed, and which provides not only for the proper clearance for a pipe through the floor, but also provides for the support of the pipe, if desired, and also for the attachment of floor and ceiling plates without the necessity of fastening such floor and 40 ceiling plates to the pipe itself.

The invention is illustrated in the accompanying drawing, in which I show a preferred form of the invention, in said 45 drawing Figure 1 being a vertical section of the device, and Figure 2 a top view of a lower member of the construction shown in Figure 1.

In said drawing 10 is the outlined floor, 50 the term "floor" in this specification referring to the cement or other mastic mass that is placed green or wet into position and is allowed to set or dry, this being done by the erection of what is known as centering, 55 on which the mass of the floor is supported

until it is set sufficiently to permit the removal of such support or centering.

The insert includes a lower tubular member 11, which has a flange 12 which is adapted to be placed so that it is substantially 60 flush with the bottom face of the floor, which becomes the ceiling of the next lower compartment. The annular flange 12 is provided with means that are adapted to permit the securing of the lower member 65 in position, and for this purpose I provide slots 13 or similar recesses so that the insert can be nailed or otherwise secured in place to the centering, and the substantially tubular part 11 projects up from the 70 centering to maintain the position and alignment of the parts that go to make up the device.

A sleeve 14, preferably of sheet metal, such as galvanized iron, is placed around 75 the tubular member 11 and rests on the flange 12, the sleeve 14 being made the desired length, according to the thickness of the floor, and can be made long enough so that it terminates at the top edge of the floor 80 that is on a level with the wearing surface, or, if desired, it can be provided with a top member which, in the form shown, consists of the tubular part 15 having the flange 16 which is adapted to be placed substantially 85 on a level with the top dressing, such level being shown in dotted outline at 17 in Figure 1.

It will thus be seen that when the top or upper member is used, the sleeve 14 rests 90 against the flanges 12 and 16 and encloses the inner ends of the tubular members, and when the cement or other plastic material is put in place on the centering the alignment and diameter of the opening are 95 preserved.

If desired, a suitable floor plate 18 is placed over the pipe, and screws 19 or other similar means can be employed for securing it to the flange 16. The ceiling plate 20 at 100 the bottom of the insert is placed around the pipe and is secured to the flange 12, the securing means illustrated consisting of screws 21 which pass through holes in the ceiling plate 20 and through the perforations 22 in the flange of the lower member of the insert.

On the rear face of the flange I prefer to place anchors 23, these being usually made so that they have a slight overhang, that is, 110

they are slightly larger at the top than at the bottom, or they can be provided with suitable irregularities to secure their being held against withdrawal from the cement 5 when the cement sets. In order to localize the expansion and contraction, and also the support of the pipe, selected, or, if need be, all of the inserts in a length of pipe extending through the floors of the building can 10 be supported from the insert.

Screws 24 are placed through openings, which openings are at an angle to the bore or axis of the insert, and preferably, for the purpose of making them accessible, open 15 downwardly through the bottom face of the flange 12, and these screws can be screwed in until they engage the pipe 25, which is shown in Figure 1 in its place within the insert, and thus support the pipe at this 20 point.

In this insert the finish of both the floor and the ceiling is neat, since there is no securing of the floor and ceiling plates to the pipe, these being secured to the insert, and 25 the usual sliding down of the ceiling plates on the pipe, due to shrinkage or for other reasons, is avoided.

The faces of the flange 12 and also of the flange 16 can be roughened, that is, they can 30 be unfinished or they can be artificially roughened, if need be, so that there is a good surface for the binding of the cement to the insert, although the bottom face of the flange 16 can be made smooth; in other 35 words, the casting can be finished if it is used on a wood floor.

The upper tubular member 15 usually extends above the floor line. This is desirable in many cases, especially where outlets in 40 cement floors in factories are established to permit the passage of water on the floor, due for instance, either to flushing or to the operation of sprinkler systems, in which case the water covers the floor only to a very 45 slight extent, and it is prevented by the upper end of the member 15 from passing down around the pipe to the floor below.

It will also be evident that in this insert the lower member 11 can be nailed or otherwise fastened directly to the centering. It 50 is not necessary to cut the centering, and when the centering is removed there is a flush surface provided on which to place the plaster of the ceiling.

It will be evident that minor changes can 55 be made in the details of parts and in the general construction without departing from the scope of the invention.

I claim:

1. An insert for concrete or similar floors comprising a lower tubular member with an annular flange at the bottom, said flange having anchor elements on its top face, an upper tubular member with an annular flange, a 65 metal sleeve between the flanges and enclos-

ing the inner ends of the members, and means in one of said tubular members for supporting a pipe, said flange serving as a member for securing the support on centering so as to withstand the pouring of cement around the member. 70

2. An insert for concrete or similar floors comprising a tubular member having an annular flange, slots in the periphery of said flange, and anchors on the rear face of said 75 flange, the slots providing means for securing the member to a centering so that the member can withstand the pouring of concrete around it, the anchors securing the member in place after the concrete sets. 80

3. An insert for concrete or similar floors comprising a tubular member having an annular flange, the flange having slots in its periphery to provide for its secure attachment to a centering, inclined perforations 85 extending to the inside of the tubular member, and screws in said perforations and adapted to project therefrom to engage a pipe in the insert.

4. An insert for concrete or similar floors 90 comprising a tubular member having an annular flange, the flange having slots in its periphery, inclined perforations extending to the inside of the tubular member, screws in said perforations and adapted to project 95 therefrom to engage a pipe in the insert, a ceiling plate, and means for securing said ceiling plate to the bottom face of the flange, whereby the first mentioned screws are concealed, and a tubular structure resting on 100 the flange and extending upward therefrom and to a sufficient distance to form a passage through concrete formed around the device.

5. The combination of a cement or similar 105 floor with an insert embedded in said floor and including a tubular element with an annular flange thereon, the annular flange being adapted to be placed adjacent to the top surface of the floor, and the tubular member being adapted to extend above the surface of the floor, and adapted to provide for the passage of a pipe and to prevent surface water on the floor passing into said insert. 110

6. An insert for cement floors comprising 115 a lower tubular member with a flange at the bottom and having its main portion of substantial length, a sleeve surrounding said portion, and resting on the flange so as to prevent cement when formed from entering 120 said member or sleeve, said flange forming means whereby the device is secured to centering so that said member and sleeve are not affected or displaced by the flow of cement.

7. An insert comprising a rigid tubular 125 member with a flange at the bottom, the flange acting as a means whereby the device can be secured to centering, and anchor elements on the top face of the flange. 130

8. An insert comprising a rigid tubular

member with a flange at the bottom, the flange acting as a means whereby the device can be secured to centering, and anchor elements on the member, whereby the flange can be used to hold the device on a centering to withstand the pouring of cement and the anchor elements to hold the device in the cement after the centering is removed.

9. An insert comprising a rigid tubular member with a flange at the bottom, the flange acting as a means whereby the device can be secured to centering, anchor

elements on the member, and means on the member for supporting a pipe within it.

10. An insert comprising a rigid tubular member with a solid part to rest on centering and thereby providing means for fastening it to the centering, and anchor elements on the member to hold said member in concrete after the centering is removed. 20

In testimony that I claim the foregoing, I have hereto set my hand, this 23rd day of September, 1919.

CHAS. H. FAY.
